BUFFING WHEEL

Harry Zimmerman, Toronto, Ontario, Canada,
assignor to Beulah Belle Zimmerman, Toronto,
Ontario, Canada

Application January 17, 1935, Serial No. 2,196

22 Claims. (Cl. 51—193)

My invention relates to improvements in buffing wheels, and the object of my invention is to provide a buffing wheel incorporating the use of pleated strips as some of the buffing layers, such strips being wound around the axis of the buff in substantially the same manner as shown in my United States Patent No. 1,927,862 with the provision of my present changes and alterations as shall hereinafter appear.

10 One of the objects of my present invention is to provide a buffing wheel comprising a plurality of layers wherein some of the said layers are plain fabric discs and other sections formed of pleated fabric which are positioned in the 15 form of rings and attached to the plain fabric layers.

Another and important object of my invention is to position some of the pleated rings with their inner face edges attached to the fabric discs intermediate of the radii of the fabric discs so that such pleated rings are only contained within the outer portion of the buff and thus build up the buff in the outer portion thickness, and a further and also particular object of my invention is to secure the inner base edge portions 25 of the pleated rings to the plain fabric discs by a plurality of substantially straight lines of stitching positioned in tangential relation to the centre of the ring, as shall be hereinafter explained.

My invention consists of a buffing wheel constructed and arranged all as hereinafter more particularly described and illustrated in the accompanying drawings in which:—

35 Figure 1 is a plan view of a buffing wheel section constructed according to my invention, the outer plain fabric disc being shown unsewn and folded back.

Figure 2 is a schematic view showing the 40 perimposed layers of pleated fabric forming part of a section.

Figure 3 is a perspective view of a fragmentary portion of pleated fabric from which the pleated rings are formed.

45 Figure 4 is a reduced plan view of a buffing wheel section wherein the pleated rings are similarly positioned within the section.

Figure 5 is a side elevational view of the section shown in Figure 4.

50 Figure 6 is a similar view to Figure 4 showing a buffing wheel section containing pleated rings positioned to provide a buff section of uniform thickness.

55 Figure 7 is a side elevational view of the section shown in Figure 6.

Figure 8 is a plan view of a buffing wheel wherein the illustrated section is made up of a plurality of flat fabric strips sewn to a plain fabric disc.

Figure 9 is a plan view of a piece of fabric from which the strips shown in Figure 8 are cut.

Figure 10 is a plan view of a buffing wheel showing one type of stitching which may be used for uniting the various sections making up the buff, and

10 Figure 11 is a perspective view of a larger type of buff which is shown partly broken away to disclose two forms of pleated rings which are incorporated therein.

Like characters of reference indicate corresponding parts in the different views in the drawings.

My buffing wheel as illustrated in Figures 1 and 2 comprises a plurality of plain fabric discs 1 each having a central spindle-receiving 20 orifice 2. A number of these plain discs carry pleated rings 3 which are formed from lengths of pleated material 4 as illustrated in Figure 3, the material being in pleated strip form and the pleats secured in place by a line of stitching 5 25 in the vicinity of one edge. In making the buffing wheel, a pleated strip is laid upon a plain disc layer with its sewn edge innermost and laid in a plurality of substantially straight lines positioned in tangential relation to the centre 30 of the ring. The pleated ring is then sewn to the plain disc layer as with a line of sewing 6. As illustrated in Figure 1, the inner edge of the 35 pleated ring is of hexagonal form, though, of course, the outline of any straight-sided figure can be followed. It will thus be seen that the pleated portions 7 extending from the straight base edges remain in substantially closed form and that the pleated portions 8 radiating from the corners 9 are distended from the base edge to the periphery. When the pleated strips are 40 first sewn in this position the outer edges are also of the same contour as their inner or base edges, but during the course of construction they are cut around their outer edges to circular form.

45 By placing the pleated strips in hexagonal or other straight-sided figure form, I have provided the corners 9 which are a greater distance from the centre of the wheel than the straight sides so that as the wheel becomes worn down in use the 50 corners are first worn or cut away before the straight base edges are reached, and in this way there is no possibility of the pleated strip being torn from out of the buff as the buff is worn down to approach the lines of sewing securing the 55 pleat-

ed layers to the plain discs. If the pleated layers were secured to the plain discs in circular form, the circular lines of stitching would be reached and severed as units as the buff was worn down, 5 with the possibility of the remainders of the circular rings being violently torn out of the buff during operation. With my present construction the wearing down of the buff gradually cuts across the lines of attachment sewing between the plain 10 discs and the pleated rings whereby the rings are not cut entirely loose.

As the portions 8 of the pleats are distended, they, of course, do not contain the same thickness of fabric as do the non-distended pleated 15 portions 1, and if the buff section is built up so that the pleated rings are all in the same position as illustrated in Figures 4 and 5, a buff will be produced wherein certain portions 10 of the edge are thicker than other portions 11. This 20 type of buff finds a use in cases where it is desired to obviate cutting marks on the article being buffed, as the cutting edges of the fabric are of undulated form and, therefore, will not make straight cutting marks.

25 In Figures 6 and 7, I show a buffing wheel 12 wherein the pleated rings are in staggered relation to one another, that is, the corners 9 of the ring overlap the straight sides of another ring. By this construction the buffing wheel approaches 30 a uniform thickness.

In Figure 8 I show an alternative construction wherein a section of the buffing wheel is made up of a plurality of fabric strips 13 which are cut from a length of fabric 14 as illustrated in 35 Figure 9. These fabric strips 13 are of trapezoidal form and their end edges 15 are so cut that when the strips are laid around a centre, as illustrated in Figure 8, they form a hexagon. The strips are laid upon a plain fabric disc 16 and are sewn 40 thereto by a hexagonal line of stitching 17. After the buff section is built up in this form it is circularly cut as around the dotted line 18.

Figure 11 shows my buffing wheel incorporating two types of pleated fabric rings, that is, a ring 19 45 having its base edge 20 of circular form as shown in my United States Patent No. 1,927,862 and also a pleated ring 21 of hexagonal form and attached to a plain fabric disc 22 by lines of stitching 23. The outer ring 21 is provided to build up the outer 50 thickness of the buff, as due to the long pleats extending from the centre of the buff to the periphery in the section 19, such pleats are considerably distended and reduce the thickness of the buff, it being understood that such a buffing 55 wheel is generally made up of a plurality of layers 19, plain discs 22 and outer pleated rings 21.

One of the particular features of my buff construction is to form the core or centre portions 24 of the buffs of a cheap fabric, such as burlap, 60 the burlap sections making up the central thickness of the buff to correspond to the inner edge thicknesses of the pleated rings, the burlap sections being preferably secured to the plain disc sections by circular rings of stitching 25. I also 65 in practice so cut the fabric strips that the outer or cutting edges are on a bias to the material, whereby ravelling is obviated. I also preferably form the pleated rings of one thickness of pleated material and join the ends by a row of stitching 70 26. Upon reference to Figures 1 and 11 of the drawings, it will be seen that I space the pleated rings away from the fabric cores 24 so that an air pocket is provided, and this air pocket in conjunction with the air spaces or pockets formed 75 between the pleated rings and the plain fabric

discs tends to keep the buffs comparatively cool in operation.

While I have specified my rings as being pleated, it is to be understood that the term "pleated" is considered to be synonymous with "puckered" or "gathered". In the drawings I have shown what are called "buff sections" and it will be understood that a number of these sections are fitted side by side upon a spindle to form what is known as a "buffing wheel".

10 While I have illustrated and described particular embodiments of my buffing wheel, it will be appreciated by those conversant with the art that my invention is susceptible to certain changes and alterations without departing from the spirit 15 thereof as set forth in the appended claims.

What I claim as my invention is:

1. A buffing wheel section comprising a plurality of fabric layers, one of the layers being a pleated strip having its pleats extending from 20 its inner base edge towards the periphery of the wheel, the strip being so arranged that some of the pleats remain in substantially closed form from the inner base edge to the periphery and some of the pleats distended from the base edge 25 to the periphery.

2. A buffing wheel section comprising a plurality of fabric layers, several of the layers being pleated strips having their pleats extending from their inner base edges towards the periphery of 30 the wheel, such strip being so arranged that some of its pleats remain in substantially closed form from the inner base edge to the periphery and some of the pleats distended from the base edge to the periphery, the pleated layers being so 35 placed in relation to one another that the distended pleats of one layer are in the same part of the wheel as the closed pleats in another pleated layer.

3. A buffing wheel section comprising a plurality of fabric layers, one of the layers being a plain disc, another layer being a pleated strip bent around the centre of the wheel and having a plurality of its pleats distended and radially extending from its inner base edge towards the 45 periphery of the wheel, the pleated layer being attached to the plain disc layer.

4. A buffing wheel section comprising a plurality of fabric layers, one of the layers being a plain disc, another layer being a pleated strip 50 bent around the centre of the wheel in substantially the form of a ring and having its pleats extending from its inner base edge towards the periphery of the wheel, the pleated strip being arranged with its base edge portion in a plurality 55 of substantially straight lines and attached to the plain disc layer.

5. A buffing wheel section comprising a plurality of fabric layers, one of the layers being a plain disc, another layer being a pleated strip 60 having its pleats extending from its inner base edge towards the periphery of the wheel, the pleated layer being attached to the plain disc layer, and a hub portion formed of fabric and attached to the plain disc layer and surrounded 65 by the pleated strip layer.

6. A buffing wheel section comprising a plurality of fabric layers, one of the layers being a plain disc, another layer being a pleated strip having its pleats extending from its inner base 70 edge towards the periphery of the wheel, the pleated strip being arranged with its base edge portion in a plurality of substantially straight lines and attached to the plain disc layer, and a hub portion formed of fabric and attached to the 75

plain disc layer and surrounded by the pleated strip layer.

7. A buffering wheel section comprising a plurality of fabric layers, one of the layers being a plain disc, another layer being a pleated strip having its pleats extending from its inner base edge towards the periphery of the wheel, the pleated layer being attached to the plain disc layer, and a hub portion formed of fabric and attached to the plain disc layer and surrounded by the pleated strip layer which is spaced apart from the hub.

8. A buffering wheel section comprising a plurality of fabric layers, one of the layers being a plain disc, another layer being a pleated strip having its pleats extending from its inner base edge towards the periphery of the wheel, the pleated strip being arranged with its base edge portion in a plurality of substantially straight lines and attached to the plain disc layer, and a hub portion formed of fabric and attached to the plain disc layer and surrounded by the pleated strip layer which is spaced apart from the hub.

9. A buffering wheel section comprising a plurality of fabric layers, one of the layers being a plain disc, and another layer in the form of a ring spaced away from the centre of the wheel and attached to the plain disc by a plurality of substantially straight lines of stitching positioned in substantial tangential relation to the centre of the ring.

10. A buffering wheel section comprising a plurality of fabric discs, fabric hub portions positioned between the fabric discs, and pleated fabric rings positioned around the hub portions and stitched to adjoining fabric discs.

11. A buffering wheel section comprising a plurality of fabric discs, hub portions positioned between the fabric discs, and pleated fabric rings positioned around the hub portions and stitched to adjoining fabric discs.

12. A buffering wheel section comprising a plurality of fabric discs, fabric hub portions positioned between the fabric discs, and pleated fabric rings positioned around the hub portions and stitched along a plurality of substantially straight lines to adjoining fabric discs.

13. A buffering wheel section comprising a plurality of fabric layers, one of the layers being a pleated strip bent around the centre of the wheel in substantially the form of a ring and having its pleats extending from its inner base edge towards the periphery of the wheel, the pleated strip being arranged with its base portion in a plurality of substantially straight lines and attached to an adjacent layer.

14. A buffering wheel section comprising a plurality of fabric buffering layers, one of the layers being a strip of fabric bent around the centre of the wheel in substantially ring form, a line of stitching in the buffering portion of the wheel and securing the ring to an adjacent layer, said line of stitching being so positioned that it angularly crosses the periphery of the wheel as the wheel is worn down to a point where its periphery severs the line of stitching.

15. A buffering wheel section comprising a plu-

rality of fabric layers, one of the layers being a buffering strip of fabric bent around the centre of the wheel in substantially ring form and having its inner edge of non-circular contour.

16. In a buffering wheel section, a plain disc of fabric extending to the periphery of the wheel, a buffering strip of fabric bent around the centre of the wheel in substantially ring form and positioned beside the plain disc fabric, gathers formed in the material at the inner edge of the ring and distending towards the outer edge of the ring to present a substantially unbroken zig-zag buffering edge, and means for securing the disc and ring in assembly.

17. A buffering wheel section comprising a plurality of fabric layers, one of the layers being a buffering bias cut strip of fabric bent around the centre of the wheel in substantially ring form and having its inner edge of non-circular contour.

18. In a buffering wheel, a plurality of plain buffering discs extending to the periphery of the wheel, a plurality of gathered buffering strips bent around the centre of the wheel in the form of rings and positioned between the fabric discs, and means for securing the rings and discs in assembly.

19. A buffering wheel section comprising a plurality of fabric layers, one of the layers being a buffering strip of fabric bent around the centre of the wheel in substantially ring form, the inner edge of the ring being so arranged that it angularly crosses the periphery of the wheel as the wheel is worn down to the inner edge of the ring.

20. A buffering wheel section comprising a plurality of fabric layers, one of the layers being a plain disc with a central orifice, another layer being a gathered strip bent into a ring substantially concentric with the orifice in the disc and having its gathers distending from its inner base edge towards its periphery, a fabric hub having a central orifice and surrounded by the pleated strip layer, and means for securing the layers and hub in assembly.

21. A buffering wheel section comprising a plurality of fabric layers, one of the layers being a plain disc with a central orifice, another layer being a gathered strip bent into a ring substantially concentric with the orifice in the disc and having its gathers distending from its inner base edge towards its periphery, a fabric hub having a central orifice and surrounded by the pleated strip layer, and stitching passing through one of the layers and the hub for securing them in assembly.

22. A buffering wheel section comprising a plurality of fabric layers, one of the layers being a plain disc with a central orifice, another layer being a fabric buffering ring formed with overlapping portions therein, such overlapping portions extending from the inner periphery to the outer periphery of the ring, a fabric hub having a central orifice and surrounded by the ring layer, and means for securing the layers and hub in assembly.

HARRY ZIMMERMAN.
